UNITED STATES PATENT OFFICE

133,795

DESIGN FOR A COMBINED CANNULA AND HUB

William Erhard, North Bergen, N. J., assignor to
E. R. Squibb & Sons, New York, N. Y., a corporation of New York

Application January 14, 1942, Serial No. 105,206

Term of patent 14 years

To all whom it may concern:

Be it known that I, William Erhard, a citizen of the United States, residing at North Bergen, in the county of Hudson and State of New Jersey, have invented a new, original, and ornamental Design for a Combined Cannula and Hub, of which the following is a specification, reference being had to the accompanying drawing, forming part thereof.

Fig. 1 is a top plan view of a combined cannula and hub embodying my new design; and

Fig. 2 is a side elevational view thereof.
The bottom of the hub portion is substantially plain and flat.

I claim:
The ornamental design for a combined cannula and hub, substantially as shown and described.

WILLIAM ERHARD.
